UNITED STATES PATENT OFFICE.

CHARLES F. LANCASTER, OF FIFE LAKE, MICHIGAN.

SPRING-SEAT FOR VEHICLES.

SPECIFICATION forming part of Letters Patent No. 290,437, dated December 18, 1883.

Application filed September 24, 1883. (No model.)

To all whom it may concern:

Be it known that I, CHARLES F. LANCASTER, a citizen of the United States of America, residing at Fife Lake, in the county of Grand 5 Traverse and State of Michigan, have invented certain new and useful Improvements in Spring-Seats for Vehicles; and I do hereby declare the following to be a full, clear, and exact description of the invention, such as will 10 enable others skilled in the art to which it app pertains to make and use the same, reference being had to the accompanying drawings, and to letters or figures of reference marked thereon, which form a part of this specification.

15 This invention relates to certain new and useful improvements in spring-seats for vehicles, its object being to provide a spring which will prevent a side and back motion; also, to provide a seat which will have an easy vertical movement, which spring will not project 20 in front of the seat; and it consists in providing a seat with a straight supporting-bar with downwardly-projecting lugs, which will rest upon the side-boards of a wagon, said seat 25 having attached to the under side of the same front springs, which project laterally, and rearwardly-projecting springs, which are attached to the front portion of the under side of the seat, said springs being clipped, respectively, 30 to the side and rear ends of the supporting-bar, the construction and arrangement of the parts being illustrated in the accompanying drawings, in which—

Figure 1 is a perspective view; Fig. 2, a side 35 view, and Fig. 3 a detailed perspective view of one of the side springs detached.

In the accompanying drawings, which illustrate my invention, A represents a seat of ordinary construction, to the front portion of 40 which are attached springs B B, the upper ends of which are attached to the under side of the seat near its front edge and at a slight distance from the side edges. This spring is curved downwardly, as shown at b, and its lower end 45 is provided with an eye, b', which is formed by bending the metal upon itself. The straight upper portion of this spring is provided with two or more perforations, by means of which it is secured to the under side of the seat by 50 bolts or other attaching means. C represents

a double curved spring, which is attached to the under side of the seat A adjacent to its edges, said spring having a straight front portion, c, and a double central curved portion, a, the end opposite the straight end c being 55 bent over upon itself, so as to form the spiral, as shown at a', the extreme end of the spring within the spiral being bent upon itself, so as to form an eye. These springs B and C are attached to a straight bar of malleable iron, (indicated by the letter D.) This bar is provided with downwardly-projecting lugs d, d, and at its front end with a downwardly-projecting portion, d'. Opposite this front lug, d', are bent at right angles therewith two horizontal wings, 60 d", d", which are perforated for the reception of the bolt e, which passes through the eye b', formed on the end of the spring B.

At the rear end of the bar are provided two upwardly-projecting wings, f, through which 70 passes a bolt for the purpose of attaching thereto the end of the spring C. The downwardly-projecting lugs formed on the under side of this bar and the downwardly-projecting portion d' embrace the upper edge of the side-boards of a wagon and hold the seat from lateral displacement. It will be noticed that 75 by the construction hereinbefore described this bar D is made of a single piece of metal, the lugs and wings or clips being formed therefrom.

In a seat provided with springs and a supporting-bar, or constructed as hereinbefore described, all side and backward and forward movement of the seat is prevented, and the 85 seat will have an easy vertical movement. A seat thus constructed is very light and durable, and the springs will brace the seat in both directions, and said springs will not form an obstruction in getting in and out of the wagon, 90 as they do not extend in front of the seat. The same is ornamental, and will add considerably to the appearance of the vehicle.

Having thus described my invention, what I claim as new, and desire to secure by Letters 95 Patent, is—

1. In a spring-seat for vehicles, the springs B B, attached to the front edge of a seat, and the rearwardly-projecting springs C C, placed at right angles with the front springs, said 100

springs being connected to each other by a rigid seat-supporting bar, substantially as described.

2. In combination with a vehicle-seat, the 5 springs B B, having their outer ends curved downwardly and inwardly, and the spring C, attached to the seat at right angles with the front spring and secured to each other by a rigid connecting-bar having downwardly-projecting lugs formed upon the same, substantially 10 as described.

3. The connecting and supporting bar D, having a flat under surface, and provided at its ends with downwardly-projecting lugs 15 formed integral therewith, and having attached to said bar upwardly-projecting springs, substantially as shown.

4. The supporting-bar D, having downwardly-projecting lugs and provided with outwardly-projecting side pieces or wings d" at 20 its front end, and upwardly-projecting side pieces or wings f at its rear end, in combination with the springs B and C, having eyes

formed at their lower ends, the same being attached to a seat, substantially as shown. 25

5. In a spring wagon-seat, the springs C C, attached near the front portion of the seat parallel with its sides, said springs projecting downwardly under the seat, and provided with coiled ends a' a', and springs B B, attached 30 under the front edge of the seat and parallel to said edge, with downwardly-curved portions, in combination with the bars D D, having downwardly-projecting lugs d and upwardly-projecting side pieces f at its rear end and 35 outwardly-projecting pieces d" d" at its front end, forming a means for attaching the springs thereto, the parts being organized and combined substantially as shown.

In testimony whereof I affix my signature in 40 presence of two witnesses.

CHARLES F. LANCASTER.
